INFLATION UNIT FOR INFLATABLE
FLOTATION DEVICES

John A. Honegger, Bloomfield, and Alvin W. Keshan, Belleville, N. J., assignors to Kidde Manufacturing Co., Inc., Bloomfield, N. J., a corporation of Delaware

Application November 26, 1942, Serial No. 467,038

5 Claims. (Cl. 222—3)

The present invention relates to inflation units for inflatable flotation devices, such as life vests, life belts, life rafts and similar life-saving devices adapted to be inflated by a compressed or liquefied gaseous medium; and more particularly to an improved connection for attaching the inflation units to the flotation devices.

An object of the invention is to provide an improved connection for attaching an inflation unit to an inflatable flotation device.

Another object is to provide a connection of the foregoing character which comprises a minimum number of parts adapted to be readily assembled in a convenient manner.

Another object is to provide a connection which facilitates removal of the inflation unit from the flotation device for the purpose of replacement of parts or repairs.

Another object is to provide a connection having a minimum number of points at which leakage may occur.

A further object consists in the features of construction, the combination of elements, and the arrangement of parts, whereby the foregoing objects may be accomplished.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for the purposes of illustration and description and is shown in the accompanying drawing, forming a part of the specification, wherein:

Figure 1 is a schematic side view of a life-preserver of the vest type, provided with an inflation unit in accordance with the present invention.

Figure 2 is an enlarged side elevational view of an inflation unit, illustrating an embodiment of the invention.

Figure 3 is a sectional view taken along the line 3—3 on Figure 2.

Figure 4 is a sectional view similar to Figure 2, illustrating a modified embodiment of the invention.

Figure 5 is a sectional view taken along the line 5—5 on Figure 4.

Referring to the drawing, and more particularly to Figure 1, there is shown, by way of example, an inflatable life-preserver 10 constructed of rubberized or other suitable fabric. The life-preserver is of the type provided with an

opening 11 through which the wearer may insert his head, and has a strap 12 adapted to be adjusted around the waist of the wearer and has a crotch strap 14 adapted to be positioned between the legs of the wearer.

At a convenient location, an inflation unit 15 is attached to the life-preserver 10. The inflation unit comprises a body member 16 having a chamber 17 for housing or storing a cartridge 19 (Figure 2) containing an inflating medium such as liquefied carbon dioxide, compressed air or the like, a cap 20 removably secured to one end of the body member 16 adapted to seal the chamber, and suitable means for releasing the inflating medium from the cartridge 19.

The releasing means may be similar to the arrangement shown in United States Patent No. Reissue 20,047, wherein a pin pierces a sealing disc or closure of the cartridge to thereby release the inflating medium into the chamber of the body member. The pin of such means is adapted to be actuated by a lever 21, as shown herein (Figure 1), which may be rocked about its pivot by a pull cable or cord 22 having a manually engageable handle or button 24 at its free end. Since the releasing means, which may be employed, are well known and do not constitute a part of the present invention a detailed description thereof is not necessary. The lever 21 is not shown in Figure 2, to simplify the view, but it will be understood that the lever is adapted to be pivotally mounted in the slot 25 at the lower end of the body member.

The inflation unit is attached to the life-preserver as about to be described with reference to Figure 3. The life-preserver has a circular centrally apertured base 30 secured thereto which preferably is formed of rubber and has molded therein an annular flange or washer 31. A stem 40 or tube 32, provided with a passage 33, has one end secured to the washer 31 and has its other end attached to the body member 16 of the inflation unit, whereby the passage 33 is adapted to conduct the inflation medium from the chamber 17 to the inflation compartment of the life-preserver. Preferably, a check valve 28, of the commercial pneumatic automobile tire type, is screw threaded into the passage of the stem, which is adapted to permit the inflation medium 50 to pass towards the inflation compartment of the life-preserver and prevents return flow of the medium towards the chamber 17.

In order to facilitate connection between the body member 16 and the stem 32, the body member is provided with a portion 34, adjacent to,

and off-set with respect to, the chamber 17, wherein a well or socket 35 is formed which is tangentially disposed to the chamber and is placed in inflation medium flow communication with the chamber by an aperture or opening 36. The socket 35 may have a substantially annular shoulder or abutment 37 upon which may be seated a sealing gasket or ring 39, and may have a threaded portion 40 adjacent the opening of the socket. Preferably, the socket is interiorly threaded and the shoulder is formed inwardly of the threads.

The free end of the stem or tube 32 is adapted to be inserted into the socket and is provided with an outwardly projecting annular flange 41 spaced from the free end, one side of which is adapted to abut the gasket 39. The other side of the flange 41 is adapted to be engaged by a connecting member for urging the flange toward the shoulder, such as a ferrule coupling nut, or sleeve 42 telescoped about the stem 32. The ferrule may have an exteriorly threaded portion 44 adapted to be screwed into engagement with the threaded portion 40 of the socket and may be provided with a nut-like portion 45 at its outer end for facilitating engagement of the ferrule by a suitable tool. When the ferrule is secured into the socket, the stem is securely connected to the body member 16, and the gasket 39 forms a leak-proof seal.

Suitable means may be provided to prevent relative rotation between the stem and the body member. For example, as shown in Figure 3, the base of the socket may be provided with a tongue or projection 46 adapted to fit into a longitudinally extending slot or groove 47 at the inserted end of the stem.

In Figures 4 and 5 the socket is provided with an octagonal bore portion 49 adapted to receive a complementary portion 50 formed on the exterior on the stem adjacent the end thereof. If desired the bore portion 49 and the stem portion 50 may be square, hexagonal or may have any other suitable shape. With this arrangement the body member 16 may be mounted and secured on the stem in various positions of angular adjustment with respect to the life-preserver.

It will be noted also that the shoulder 37 and the flange 41, in addition to compressing the gasket 39 to form a seal, serve to space the free end of the stem from the base of the socket, whereby the inflation medium passing through the aperture 36 and entering the socket is adapted to flow through the passage 33 of the stem.

From the foregoing description it will be seen that the present invention provides an improved inflation unit and a connection for attaching the unit to an inflatable device. The unit and its connection comprise a minimum number of parts which are readily assembled or taken apart for repairs. The connection is leakproof and prevents the loss of the inflating medium. The parts of the unit are rugged in construction and can readily withstand any rough usage to which they may be subjected.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

It is also to be understood that the following claims are intended to cover all the generic and specific features of the invention herein described,

and all statements of the scope of the invention which, as a matter of language, might be said to fall therebetween.

We claim:

- 5 1. An inflation unit for attachment to one side of an inflatable flotation device, comprising an elongated body member having a chamber for storing a container of fluid pressure medium to inflate the flotation device and provided on one side with an offset portion formed with a socket defined by an inner end face and extending tangentially with respect to said chamber and communicating with the latter adjacent said inner end face, said socket having a shoulder, a stem having a passage therein provided with a valve and adapted to conduct and control fluid medium from said chamber to the flotation device, said stem having an inner radial face disposed in spaced relation with said inner end face and provided with a flange arranged a predetermined distance from said radial face, and means carried on said stem and detachably secured to said offset portion for coupling said stem to said portion in fixed relation, said shoulder coacting with 10 said flange in a manner to position and maintain said radial face of said stem in said spaced relation to said inner end face of said socket for permitting communication between said chamber and said socket at all times.
- 15 2. An inflation unit for an inflatable flotation device, comprising a body member having a chamber for storing a container of fluid pressure medium adapted to inflate the device, said body member having a socket formed with a shoulder and extending tangentially with respect to said chamber and defined by an inner end face, said body member formed with an opening effecting communication between said chamber and said socket adjacent said inner end face, a stem having a passage therein provided with a valve and adapted to conduct and control fluid medium from said chamber to the flotation device, said stem having one end disposed in said socket and provided with a flange arranged a predetermined 20 distance from said end of said stem, and a member securing said stem to said body member and engaging said flange to maintain the latter in sealed relation with said shoulder, said shoulder cooperating with said flange to maintain said end of said stem in spaced relation to said inner end face and thus permit communication between said chamber and said socket through said opening at all times, said body member and said stem having cooperating portions for preventing rotation therebetween.
- 25 3. An inflation unit for an inflatable flotation device, comprising a body member having a chamber for storing a container of fluid pressure medium adapted to inflate the device, said body member having a socket formed with a shoulder and extending tangentially with respect to said chamber and defined by an inner end face, said body member formed with an opening effecting communication between said chamber and said socket adjacent said inner end face, a stem having a passage therein provided with a valve and adapted to conduct and control fluid medium from said chamber to the flotation device, said stem having one end disposed in said socket and being provided with a flange arranged a predetermined distance from said end of said stem, a member securing said stem to said body and engaging said flange to maintain the latter in sealed relation with said shoulder, and sealing means between said shoulder and said flange,
- 30
- 35
- 40
- 45
- 50
- 55
- 60
- 65
- 70
- 75

said shoulder cooperating with said flange and said sealing member to maintain said end of said stem in spaced relation to said inner end face and thus permit communication between said chamber and said socket through said opening at all times, said body member and said stem having cooperating portions for preventing rotation therebetween.

4. The structure of claim 1 wherein said faces are provided with a slot and tongue respectively having interfitting relation to preclude relative rotation of said body member and stem and thus maintain said body member in fixed relation with said flotation device.

5. An inflation unit for an inflatable flotation device, comprising an elongated body member having a chamber for storing a container of fluid pressure medium to inflate the flotation device and provided on one side with an offset element formed with a socket portion extending tangentially with respect to said chamber, said socket

portion including a shoulder and having an aperture communicating with said chamber, a stem having a passage therein provided with a valve and adapted to conduct and control fluid medium 5 from said chamber to the flotation device, said stem having an opening and provided with a shoulder arranged a predetermined distance from said opening, and means detachably secured between said offset portion and said stem for coupling said stem to said portion in fixed relation, said socket shoulder cooperating with said stem shoulder in a manner to position and maintain said stem opening in predetermined relation to said aperture to provide communication between said chamber and said socket portion at all times, said body member and said stem having cooperating portions for preventing rotation therebetween.
